UNITED STATES PATENT OFFICE.

JOHN F. O'CONNOR, OF CHICAGO, ILLINOIS, ASSIGNOR TO WILLIAM H. MINER, OF CHICAGO, ILLINOIS.

DRAFT-RIGGING FOR RAILWAY-CARS.

1,073,163.

Specification of Letters Patent. Patented Sept. 16, 1913.

Application filed March 31, 1913. Serial No. 757,857.

To all whom it may concern:

Be it known that I, JOHN F. O'CONNOR, a citizen of the United States, residing at Chicago, in the county of Cook and State of Illinois, have invented a certain new and useful Improvement in Draft-Rigging for Railway-Cars, of which the following is a full, clear, concise, and exact description, reference being had to the accompanying drawings, forming a part of this specification.

My invention relates to improvements in draft rigging for railway cars.

The object of my invention is to provide a draft rigging of simple and cheap construction, and one of simple operation.

In the drawings forming a part of this specification Figure 1 is a side elevation partly in longitudinal section on line 1—1 of Fig. 2 of a draft rigging embodying my invention. Fig. 2 is a plan view partly in horizontal longitudinal section on line 2—2 of Fig. 1. Fig. 3 is a side elevation partly in vertical longitudinal section showing the position of the parts in full compression on pulling movement of the draft rigging. Fig. 4 is a side elevation partly in vertical longitudinal section showing the position of the parts under full compression in buffering movement of the draft rigging. Fig. 5 is a half cross section on line 5—5 of Fig. 1. Fig. 6 is a half cross section on line 6—6 of Fig. 1. Fig. 7 is a perspective view of the wedge housing. Fig. 8 is a perspective view of the wedge. Fig. 9 is a perspective view of the friction blocks.

Referring to the drawings 10, 10 represent draft sills, or parts of the car frame to which the draft rigging is applied, 11 the end sill, 12 the buffer block, 13 the draw-bar carry iron, 14, 14 stop members suitably secured to the draft members and in opposed relation between the same, said stop members being provided with front 15 stop shoulders 15, 16, rear limiting stop shoulders 16, 16, rear limiting stop shoulders 17, 17, and rear stop shoulders 18, 18. The foregoing parts are of well known construction.

19, 19 represent guide plates secured to the under faces of the stop members 14, 14, preferably by bolts 20, 20, and adapted to support the transversely arranged front and rear followers 21 and 22 respectively. Between the followers are located the friction

members 23 of the draft gear, the spring mechanism 24 of the draft gear being mounted back of the rear follower 22. The rear follower 22 is provided with a pair of forwardly extended limbs 25, 25 passing either side of the friction members 23 of the draft gear, and forming with the rear follower a loop or draft yoke. The limbs 25, 25 are provided near their forward ends with lateral slots 26 to receive 60 the coupler key 27. The coupler key passes through the transverse slot 28 in the draw-bar 29, and also in preferable construction through slots 30, 30 in the draft members. The slots 30, 30 in the draft members and 70 the slots 26, 26 in the limbs 25, 25 are longitudinally extended to permit the engagement of the butt of the draw-bar with the front follower 21 in buffering movement of the draft rigging without strain upon 75 the key 27.

The friction members 23 of the draft gear comprise a housing 31, a wedge 32, and friction blocks 33, 33. The housing 31 is a hollow box-like member, preferably rectangular in cross section, and open at its forward end 34 and its rearward end 35. Across the forward opening said box-like member is provided with a bar 36, preferably integral with said box-like member. 80 The said bar is preferably forwardly extended from said box-like member, as illustrated in Fig. 7 of the drawing, and is centrally provided with an opening 37; in preferable construction the said opening being through a central hub 38 with which the said bar 36 is provided. The upper and lower plates 39 and 40 respectively of the hollow box-like member of the housing are provided on their inner faces with angular friction faces 41, 41; in preferable construction the angle thereof being substantially thirty degrees to the plane of the said plates.

100 The wedge 32 comprises a block forwardly provided with a central slot 42 adapted to slidably receive the central bar 36 of the housing, the legs 43 of said bifurcated wedge forming the sides of the said slots 42 being adapted to pass at either side 105 of the bar 36 of the housing 31 when the wedge and housing are in assembled relation. The rear face 44 of the bar 36 is adapted to engage the rear end 45 of the slot 42 of the wedge when the parts of the 110

gear are in normal position. The front ends 46 of the legs 43 of the wedge engage the rear face of the front follower. The wedge is rearwardly provided with upper 5 and lower angular friction faces 47 and 48 respectively, one of said faces being opposite the lower friction face 41 of the housing, and the other of said friction faces being opposite the upper friction face. Between 10 each of the opposed friction faces of the housing 31 and wedge 32 is interposed a friction block 33, the said friction blocks being preferably three sided or triangular in cross section, and provided with friction faces 49, 49, 49, one of said friction faces engaging with a friction face of the wedge, and another friction face engaging with a friction face of the housing. The other friction face of each friction block is adapted 15 to engage the front face 51 of the rear follower 22.

The wedge 32 is provided at its rear end with a flat surface 52, which is adapted to engage the front face 51 of the rear follower 22 in full compression of the parts in buffing and draft movements of the gear. The wedge is provided with a longitudinal opening 53 registering with the opening 37 in the bar 36 of the housing.

The friction blocks 33 at their meeting edges are each provided with a groove 54, the said grooves when the friction blocks are in normal position, as illustrated in Fig. 1 of the drawings, forming an opening registering with the opening 53 in the wedge 32. A spring bolt 55 passes through the openings 37 in the housing, 53 in the wedge, and the said grooves in the friction block, and through a perforation 56 through the rear follower 22, and is rearwardly extended from the said rear follower a suitable distance to permit the mounting about the same of the spring members 24. The spring bolt 55 is forwardly provided with a head 57, and is rearwardly provided with the nut 58.

The spring members 24 preferably comprise an inner spring 59 and an outer spring 60, the said springs being forwardly seated against the rear face 61 of the follower 22, and rearwardly seated against the front face 62 of the spring seat 63, which is maintained in position upon the said spring bolt by the nut 58.

The front follower 21 is provided at either lateral edge with a notch 64 for the passage of the limbs 25, 25 of the yoke member.

On rearward movement of the draw-bar the front follower 21 moves rearwardly. The said front follower through its engagement with the forward ends of the legs 43 of the wedge 32 moves said wedge rearwardly. The rear follower 22 is stationary against the stop shoulders 18. One of the friction blocks moves upwardly and the other down-

wardly, the said blocks being forced transversely away from each other by the rearward movement of the wedge, the said blocks each being in frictional engagement with a wedging face of the wedge, a wedging face of the housing and with the forward face of the rear follower. The movement of the wedges away from each other forces the housing forwardly through the engagement between the friction blocks and the friction faces of the housing. The forward movement of the housing draws the spring bolt forwardly, thus compressing the spring members between the rear face 61 of the rear follower 22 and the spring seat 63. This movement of the parts continues until the rear face 52 of the wedge 32 engages the front face 51 of the rear follower 22. The position of the parts when in full compression in buffing movement is illustrated by Fig. 4 of the drawings. In forward movement of the draw-bar the front follower 21 is stationary against the front stop shoulders 15, 15, the wedge 32 through its limbs 43, 43 engages the front follower and is stationary, the rear follower is drawn forwardly, and the friction blocks move outwardly and forwardly in frictional engagement with the friction faces of the housing, the friction faces of the wedge and the forward face of the rear follower, and in such forward and outward movement the housing is moved forwardly, drawing the spring bolt forwardly, and compressing the spring members 24 between the spring seat 63 and the rear face 61 of the forwardly moving rear follower 22.

I claim:

1. In a draft rigging for railway cars, in combination, a draw-bar, front and rear followers, a housing, a wedge, friction blocks and a spring, the spring being forwardly seated against the rear follower, the friction blocks engaging the rear follower, the housing and the wedge, the rear follower being operatively connected to the draw bar, and the said housing and springs being moved forwardly into compression resisting action on both forward and rearward movement of the draw-bar.

2. In a draft rigging for railway cars, the combination with draft members, of parts mounted between the draft members comprising a draw-bar, followers, means connecting the rear follower to the draw bar, a housing, a wedge and transversely movable friction blocks associated with said housing, a spring back of the rear follower and connected to the housing, the wedge spreading the friction blocks, and the friction blocks on spreading moving the housing forwardly from its normal position, and the housing forwardly compressing the springs on both forward and rearward movement of the draw bar.

3. In a draft rigging for railway cars, in combination, a draw-bar, a yoke connected thereto, friction members within the yoke, a spring and spring bolt, said friction members including a bifurcated wedge, a hollow housing to receive said wedge, said housing having a bar straddled by said wedge, the friction blocks engaging the housing and wedge, and the spring bolt connecting the transverse bar of the housing with the spring to compress the same on friction movement of the blocks.

4. In a draft rigging for railway cars, in combination, a draw-bar, a yoke connected thereto, friction members within the yoke, a spring, a spring bolt, said friction members including a wedge, a hollow housing to receive said wedge, said wedge having a central slot, said housing having a transverse bar slidingly operating within said slot, the friction blocks engaging the housing and wedge, and the spring bolt connecting the transverse bar of the housing with the spring to compress the same on movement of the friction blocks.

5. In a draft rigging for railway cars, in combination, a draw-bar, stop members, front and rear followers, a wedge, a housing therefor, friction blocks, a spring bolt and a spring, the said housing having a transverse bar, and the wedge having a pair of limbs straddling said bar and engaging the front follower, the friction blocks being in sliding frictional engagement with the housing, wedge and rear follower, the rear follower having means connecting it to the draw-bar, and the spring being seated against the rear follower, and the spring bolt connecting said spring to the bar of the housing.

6. In a draft rigging for railway cars, in combination, a draw-bar, stop members, front and rear followers, a wedge, a housing therefor, friction blocks, a spring bolt and a spring, the wedge passing through said housing and engaging the front follower, the friction blocks being in sliding frictional engagement with the housing, wedge and rear follower, the rear follower having means connecting it to the draw-bar, and the spring being seated against the rear follower, and the spring bolt connecting said spring to the housing.

7. In a draft rigging for railway cars, in combination, a draw-bar, stop members, front and rear followers, a wedge, a movable member engaging said wedge, friction blocks, a spring bolt and a spring, the movable member having a bar in sliding engagement with the wedge, the wedge engaging the front follower, the friction blocks being in frictional engagement with the housing, wedge and rear follower, the rear follower having means slidingly connecting it to the draw-bar, the movable member, wedge and rear follower being perforated to re-

ceive the spring bolt, the said spring bolt connecting the movable member to the spring, and being adapted to forwardly compress said spring on movement of the said movable member.

8. In a draft rigging for railway cars, in combination, a draw-bar, stop members, front and rear followers, a wedge, a movable member slidingly engaging the wedge, friction blocks, a spring and means for connecting the movable member and spring, the movable member having friction faces, the friction blocks being in sliding engagement with said faces, the rear follower being provided with forwardly extending arms slidingly engaging the draw-bar.

9. In a draft rigging for railway cars, in combination, a draw-bar, stop members, front and rear followers, means connecting the rear follower to the draw-bar, a housing, wedge and friction blocks between the followers, a spring forwardly seated against the rear follower, a bolt engaging the spring to the housing, the wedge being in sliding engagement with the housing, and having forwardly extending means engaging the front follower, the friction blocks frictionally engaging the housing and wedge, and adapted to draw the spring forwardly into compression in both buffing and pulling movement of the draw-bar.

10. In a draft rigging for railway cars, in combination, a draw-bar, stop members, front and rear followers, means operatively connecting the rear follower of the draw-bar, a wedge, a hollow housing to receive the same and friction blocks between the followers, a spring forwardly seated against the rear follower and means connecting the spring to the housing, the housing and wedge each having angular friction faces, said friction blocks each engaging a friction face of the wedge and a friction face of the housing, said friction blocks being adapted to move transversely between the draft members and draw the spring forwardly in compressing movement in both forward and rearward movement of the draw-bar.

11. In a friction draft rigging for railway cars, in combination, a draw-bar, stop members, draft members, a loop connected to the draw-bar, a hollow housing, wedge and friction blocks within said loop, a spring without said loop and seated against the same, means connecting the spring to the housing, the housing being provided with upper and lower angular friction faces, the wedge having oppositely arranged friction faces, the friction blocks each engaging a friction face of the wedge and a friction face of the housing, and being in frictional engagement with said loop, said friction blocks being adapted to spread under wedging action and move the hous- 130

- ing forwardly in both buffing and pulling movement of the draft rigging.
12. In a draft rigging for railway cars, in combination, a draw-bar, a loop connected to the draw-bar, a housing, wedge and friction blocks within the loop, a spring seated against said loop, and means connecting the spring to the housing, the friction blocks being in engagement with the housing, loop and wedge, the said spring being adapted to yieldingly resist spreading movement of the friction blocks when said blocks are under pressure of the wedge.
13. In a device of the character described, a movable member, a wedge passing through said member, friction blocks, a spring, a transverse member interposed between the friction block and spring, and means connecting the movable member to the spring, the friction blocks being transversely displaceable by the wedge, the movable member being forwardly movable by the friction blocks, said movable member being adapted through said connecting means to draw the spring forwardly into compression against said transverse member on movement of the friction blocks.
14. In a device of the character described, a draw-bar, stop members, a wedge, a member movable relatively to the wedge, blocks in frictional engagement with said member and with the wedge, a transverse member tractively connected to the draw-bar on forward movement of the draw-bar, and in engagement with stop members on rearward movement of the draw-bar, a spring seated against said transverse member and tractively connected with said movable member, the frictional movement of the blocks actuating the spring through said movable member, and compressing the same against said transverse member both when stationary and when moving with the draw-bar.
